Primary Examiner — Dana K Weiland*Assistant Examiner* — Emily Anna Saunders(74) Attorney, Agent, or Firm — Parsons Behle & Latimer(57) CLAIM

The ornamental design for an oval pull tab game ticket, as shown.

DESCRIPTION

FIG. 1 is a top perspective view showing the oval pull tab game ticket embodying the new design with a perforation connecting the oval pull tab.

FIG. 2 is a side elevation view thereof with the right side being a mirror image thereof.

FIG. 3 is a rear elevational view thereof with the front being a mirror image thereof.

FIG. 4 is a top plan view thereof with the perforation connecting the oval pull tab.

FIG. 5 is a bottom plan view thereof.

FIG. 6 is a top perspective view of the oval pull tab game ticket in an alternate configuration with the oval pull tab partially raised; and,

FIG. 7 is a top perspective view of the oval pull tab game ticket in an alternate configuration with the oval pull tab removed.

The broken lines showing text in FIG. 6 and FIG. 7 form no part of the claimed design. The oval lines showing perforations in FIGS. 1, 4, and 6 form part of the claimed design.

1 Claim, 3 Drawing Sheets(56)
